COMPRESSOR CONTROLLING MECHANISM

Filed Nov. 21, 1929

Inventor:

Louis A. Maxson.

UNITED STATES PATENT OFFICE

LOUIS A. MAXSON, OF CLAREMONT, NEW HAMPSHIRE, ASSIGNOR TO SULLIVAN MACHINERY COMPANY, A CORPORATION OF MASSACHUSETTS

COMPRESSOR CONTROLLING MECHANISM

Application filed November 21, 1929. Serial No. 408,882.

My invention relates to means for controlling a motor driven compressor, and particularly the unloading and loading of a compressor mechanism. More particularly my invention relates to mechanism for automatically controlling the loading and unloading of a compressor in accordance with the receiver pressure.

One object of my invention is to provide improved controlling means for the mechanism which governs a compressor mechanism. Another object of my invention is to provide improved controlling mechanism designed to delay loading of the compressor when the same is starting from rest. A further object of my invention is to provide improved mechanism for actuating an unloading device for a compressor by vacuum and controlling such unloading in accordance with receiver tank pressure. Further objects of my invention will become apparent in the course of the ensuing description, and be more particularly pointed out in the appended claims.

25 In the accompanying drawing, in which I have shown, for purposes of illustration, one embodiment of my invention:

Fig. 1 is a diagrammatic view of a compressor with its unloading mechanism controlled by a system in which my invention is incorporated.

30 Fig. 2 is a detail sectional view of a valve controlling the line between the vacuum pump and the unloading mechanism for the compressor.

35 In the illustrative embodiment which is shown in the drawing, my improved controlling system is shown applied to an angle compound compressor having a low pressure cylinder 5, a high pressure cylinder 6 and an intercooler 7. Any suitable prime mover may be employed for driving the compressor; but for purposes of illustration, I have shown as driving means a synchronous motor 8 whose field is supplied with current from an exciter 9, which is driven in any usual manner. The fluid compressed by the high pressure cylinder 6 is conducted to a receiver tank 10, from which it may be supplied for use as required. The inlet 11 to the low pres-

sure cylinder 5 may be closed by a sleeve valve 12, so as to unload the compressor. A valve rod 13 is passed through the hub 14 of the sleeve valve 12. Devices 15 are mounted on rod 13, to engage opposite sides of the hub 55 14. The weight of the valve and associated parts would move it to closed position, but if desired a weight 16 may surround the rod 13, and rest upon the upper collar 15; and help to move the sleeve valve 12 into closed 60 position. A motor is mounted at the upper end of rod 13 for moving the same. Various types of motors may be used, which are adapted to be actuated by a vacuum; but for purposes of illustration, I have shown a 65 cylinder and piston 18 and 17 with the piston 17 connected to the rod 13.

A vacuum pump 20 is mounted on the side of the base of the compressor, and is actuated by a link 21 driven from the compressor crank shaft 22. A pipe line 23 connects this vacuum pump 20 with the cylinder 18. An adjustable bleeder 24 may be arranged in the pipe line 23; and is so adjusted as to permit sufficient air to enter the pipe line 23 70 during the lesser speeds of the compressor to prevent lifting of the sliding valve 12. The bleeder 24 is set so that the vacuum pump 20 will pump the pressure in the cylinder 18 low enough to raise the slide valve 12 just before the compressor comes to full speed. A valve 25 is also arranged in the pipe line 23 between the bleeder 24 and the cylinder 18. This valve 25 is shown in cross section in Fig. 2 and comprises a rotatable 75 element 26 formed with passageways so that the cylinder 18 may be connected either to the vacuum pump 20, or to a vent 27 in the casing 28 of the valve 25. A lever 29 is secured to the rotatable element 26 so as to 80 rotate the same. The armature of a solenoid 30 is connected by a link to the lever 29 for actuating the same. This solenoid is included in a circuit which is supplied with current from the exciter 9 for the motor 8. A pressure switch 31 is also included in this circuit; and is controlled by the pressure in the receiver tank 10. For this purpose the switch comprises a diaphragm 32 connected by a pipe line 33 to the receiver 85

90 95 100

tank 10. A spring 34 normally retains the switch 31 in closed position. The spring tension is adjustable so that the switch 31 will be opened when a predetermined pressure is exerted upon the diaphragm 32. When the pressure switch 31 is opened, the solenoid 30 is, of course, deenergized; and, due to a weight or spring acting on the armature, the lever 29 swings down to turn the valve element 26 into such position as to connect the cylinder 17 with the atmosphere.

The operation of my improved control system is as follows: During normal running of the compressor, the slide valve 12 is in raised position, due to the vacuum pumped by the vacuum pump 20. As pressure varies in the receiver tank 10, the same pressure variations are exerted on the diaphragm 32. The pressure switch 31 will open if a predetermined pressure, for which the spring 34 is tensioned, is exceeded; whereupon the solenoid 30 is deenergized and the valve 25 opens the cylinder 18 to the atmosphere. This permits the weight 16 to force the slide valve 12 into closed position, unloading the compressor.

When the receiver tank pressure falls below a lower predetermined point, the spring 34 closes the switch 31 and energizes the solenoid 30 so as to elevate the lever 29 into position to connect the cylinder 18 to the vacuum pump 20. This raises the slide valve 12, so as to open the inlet 11; and the compressor is again loaded.

The operation when starting up from rest is as follows: The slide valve 12 will be in lowered position, due to the admission of air through the bleeder 24, or through the vent 27 in the casing 28 of the valve 25. If the latter be true, that is to say, if the pressure switch 31 is in position to unload the compressor, the compressor comes up to speed and continues to run unloaded until the pressure in the receiver tank 10 drops to a point which produces closing of the pressure switch 31. Should, however, the vent 27 be closed and the cylinder 18 connected to the vacuum pump 20, the bleeder 24 will admit sufficient air so that the slide valve 12 will remain in lowered position until the compressor comes substantially up to normal running speed. Just prior to reaching normal running speed, the vacuum pump is driven at sufficient speed to lower the pressure in cylinder 18 to a point where atmospheric pressure acting on the lower face of the piston 17 will lift the slide valve 12.

It will be apparent that as a result of my invention I have provided an improved system for unloading a compressor. It will furthermore be apparent that my invention provides improved controlling mechanism for the loading and unloading of the compressor which, in an improved manner, pre-

vents loading of the compressor until the same has come up to speed.

While I have in this application specifically described one form which my invention may assume in practice, it will be understood that this form of the same is shown for purposes of illustration and that the invention may be modified and embodied in various other forms without departing from its spirit or the scope of the appended claims. What I claim as new and desire to secure by Letters Patent is:

1. In a compressor controlling system, a valve whose position determines the loading and unloading of the compressor, actuating means therefore operable when subjected to a predetermined subatmospheric pressure, means driven by the compressor for creating a subatmospheric pressure for acting on said actuating means, and means governed by compressor discharge pressure variations and operative during continued running of the compressor for controlling the subjecting of said actuating means to subatmospheric pressure.

2. In a compressor controlling system, an unloading device, actuating means for said device operable when subjected to a predetermined subatmospheric pressure, a vacuum pump driven by the compressor, means providing a conduit leading from the actuating means for said unloading device to said vacuum pump, a valve controlling flow of fluid through said conduit, and means governed by compressor discharge pressure variations and operative during continued running of the compressor for controlling said valve controlling flow of fluid through said conduit.

3. In a compressor controlling system, a valve whose position determines the loading and unloading of the compressor, and means for moving said valve comprising means tending to move said valve into position to unload the compressor, means actuated when subjected to a predetermined subatmospheric pressure for moving said valve into position to load the compressor, and means responsive to the speed of the compressor and communicating with said third mentioned means for creating sufficient vacuum to load the compressor when the same comes up to speed.

4. In combination with a compressor, means actuated to loading position when subjected to a predetermined subatmospheric pressure, for controlling loading and unloading of said compressor, a vacuum pump driven in accordance with the speed of the compressor for creating a subatmospheric pressure for acting on said controlling means, substantially the vacuum pumped by said vacuum pump when the normal running speed of the compressor is reached being required for producing loading of the compressor, and means for increasing the fractional

pressure to which said controlling means is subjected during loaded operation of the compressor, upon an increase in the discharge pressure of the compressor beyond a predetermined amount.

5 5. In a compressor controlling system, an unloader valve, actuating means therefor controlled by subatmospheric pressure, means for maintaining a subatmospheric pressure during running of said compressor, and means for controlling connection of said actuating means with said means for maintaining subatmospheric pressure controlled by compressor discharge pressure.

10 15 6. In a pumping system, in combination, a pump, an intake unloader therefor, means including an element responsive to subatmospheric pressure conditions for moving said valve to loading position, a second pump actuated with said first pump for producing subatmospheric conditions, and means controlled by pressure variations produced by running of said first pump controlling connection of said second pump with said

20 25 element.

7. In a compressor controlling system, a valve whose position determines the loading and the unloading of the compressor, actuating means for moving said valve to loading position when subjected to a predetermined subatmospheric pressure, a vacuum pump operative to produce said predetermined subatmospheric pressure when said compressor is operating at normal speed, means for connecting said vacuum pump with said actuating means to subject the latter to the vacuum produced by the former, and means governed by compressor discharge pressure for breaking the vacuum at said actuating means when

30 35 40 compressor discharge pressure reaches a predetermined maximum.

In testimony whereof I affix my signature.
LOUIS A. MAXSON.
